UNITED STATES PATENT OFFICE.

LOUIES H. BRINKMAN, OF BROOKLYN, NEW YORK, ASSIGNOR TO THE NEW YORK PIPE BENDING AND MACHINE COMPANY, OF SAME PLACE.

DESIGN FOR A PLUMBER'S TRAP.

SPECIFICATION forming part of Design No. 28,567, dated May 10, 1898.

Application filed January 23, 1897. Serial No. 620,477. Term of patent 14 years.

To all whom it may concern:

Be it known that I, LOUIES H. BRINKMAN, a citizen of the United States, residing in the city of Brooklyn, in the county of Kings and State of New York, have invented and produced a new and original Design for Plumbers' Traps, of which the following is a specification, reference being had to the accompanying drawings, forming a part thereof.

10 The invention relates to a design for a plumber's trap, and is illustrated in the accompanying drawings, in which—

Figure 1 represents a side view of a plumber's trap embodying the design, and Fig. 2
15 is a sectional view.

The leading feature of the design consists in the inclined or oblique disposition of the

middle member of the trap with respect to the two outer members, and in the drawings the said two outer members are marked 1 and 2 and are substantially straight, while the middle member occupies an inclined or oblique position with respect to said two outer members and is connected therewith by sweeping curves. 25

What I claim is—

The design for a plumber's trap, substantially as shown and described.

This specification signed and witnessed this 16th day of January, A. D. 1897.

LOUIES H. BRINKMAN.

In presence of—

ALFRED W. KIDDLE,
WILLIAM B. GREELEY.
